UNITED STATES PATENT OFFICE.

FRANK VERES, OF RUSSELLVILLE, KENTUCKY.

FOUNDATION FOR BUILDINGS IN EARTHQUAKE LOCALITIES.

981,824.

Specification of Letters Patent. Patented Jan. 17, 1911.

Application filed August 24, 1909. Serial No. 514,400.

To all whom it may concern:

Be it known that I, FRANK VERES, a citizen of the United States, resident of Russellville, in the county of Logan and State 5 of Kentucky, have made a certain new and useful Invention in Foundations for Buildings in Earthquake Localities; and I declare the following to be a full, clear, and exact description of the same, such as will enable 10 others skilled in the art to which it appertains to make and use the invention, reference being had to the accompanying drawings, and to letters or figures of reference marked thereon, which form a part of this 15 specification.

Figure 1 is a plan view of the invention showing the framework of the structure. Fig. 2 is a front view of the invention with parts in dotted lines. Fig. 3 is a section on 20 the line 3—3, Fig. 1. Fig. 4 is a section on the line 4—4, Fig. 1. Fig. 5 is a detail sectional view with parts broken away showing a modification.

The invention relates to foundations for 25 buildings in earthquake localities, and it consists in the novel construction and combinations of parts, as hereinafter set forth.

In the accompanying drawings, illustrating 30 the invention, the letter *a*, designates a shaft which is sunk to the bedrock *b*, or piles *c*, may be driven to form the bottom of said shaft when bedrock is not easily reached owing to the unstable nature of the ground, a smooth cement covering *g* being laid over 35 the piles, as shown in Fig. 5 of the drawings.

Fitting in the shaft *a*, and resting upon the smooth bottom *a'*, thereof, is a pillar or 40 upright column *c*, preferably of iron or steel and having a slight taper or gradually decreasing in size from top to bottom. This pillar or column is of less size in cross-section than the shaft wherein it fits, a little oil being placed in the bottom of the shaft for lubricating purposes. A number of the 45 shafts are sunk and pillars or columns placed therein as are required for the building to be erected, each pillar having preferably a vertical pin *d*, at its upper end, which engages the horizontal sill *f*, also 50 preferably of iron or steel, and connecting and resting upon the pillars. The framework of the building shown at *g*, is erected upon the horizontal sills *f*, *f*, diagonal cross

braces *h*, *h*, being provided to form a rigid structure.

A platform support *i*, is provided for the chimney *i'*, built thereupon, said platform having supporting pillars or columns *j*, *j*, fitting also in a shaft *a*, and resting upon the bottom thereof. A center platform *k*, is 55 provided for each square or section of the structure, said platform carrying a center post *k'*, of hollow character, with which the diagonal brace rods have connection by means of adjustable nuts *l*, *l*, engaging 60 threaded ends of said rods and the opposite ends of the brace rods having hook connection *m*, with eyes of the pillars or columns *c*, *c*, and the corner posts *m'*. This platform *k*, also has supporting pillars *k*², *k*², resting 65 upon the bottom of a shaft *a*.

In time of earthquake, the movement of the earth in which the shafts *a*, *a*, are located, takes place without injury to the columns or supports *d*, *d*, which slide upon the 70 smooth bottoms of the shafts, and the rigid structure of the building resting upon said columns being preserved from injury.

If desired the bottom of each shaft may be slightly dished as shown in Fig. 5 of the 75 drawings to retain the pillar or column thereof normally in the center. Towers, porches, bay windows, etc., may be provided for as will readily be apparent.

It is advisable in order to render the 80 structure rigid that from two to four strong braces be provided under each floor or room running parallel with the floor joists and made fast to the sills.

Having thus described my invention, what 85 I claim as new and desire to secure by Letters Patent is:—

1. In a foundation for buildings, the combination with a hard bed having a smooth upper bearing surface, of a rigid foundation 90 frame comprising corner pillars, horizontal stringers connecting the same, and a center post having diagonal brace connections with the corner pillars and having also a supporting pillar, said corner pillars and the supporting pillar for the center post having 95 sliding supporting engagement with the bearing surface of said bed.

2. In a foundation for buildings, the combination with a hard bed having a smooth 100 upper bearing surface, of a rigid foundation 105

frame comprising corner pillars, horizontal stringers connecting the same, a hollow center post having diagonal brace connections with the corner pillars and having also a supporting pillar, and a chimney platform having also a supporting pillar, said corner pillars and the supporting pillars for the center post and chimney platform having

slidable supporting engagement with the bearing surface of said bed.

In testimony whereof I affix my signature, in presence of two witnesses.

FRANK VERES.
